UNITED STATES PATENT OFFICE.

ANTONIO RAUSSE, OF NORTHLAKE, NEW JERSEY.

ATTACHMENT FOR EMBROIDERY MACHINES.

Application filed March 14, 1922. Serial No. 543,723.

To all whom it may concern:

Be it known that I, ANTONIO RAUSSE, a citizen of the United States, and a resident of Northvale, in the county of Bergen and 5 State of New Jersey, have invented new and useful Improvements in Attachments for Embroidery Machines, of which the following is a full, clear, and exact description.

This invention relates to attachments for 10 embroidery machines and is primarily designed for use with an automatic embroidery machine.

In the Groebli automatic embroidery machine considerable difficulty is experienced 15 from the breaking of threads by the take-up mechanism, which is normally thrown forward, slackening the threads when the fabric being worked is moved upon the completion of a figure. This is caused by the 20 sudden tightening of the threads when the machine begins to operate on the new figure. While the fabric is being moved the threads are released by the take-up device and usually a certain slackness remains, and when 25 the take-up device moves to tighten the threads when the embroidery machine begins to operate on the new figure it moves through a certain distance without meeting any resistance by the thread and finally 30 tightens the thread with a snap, the force of which is so great that some of the threads are often broken since the tensioning roller has no momentum and is started very suddenly.

35 The general object of this invention is the provision of an embroidery machine attachment adapted to be operated by the machine to release the take-up operating means when the fabric is being moved upon the completion of a figure so that the take-up means is retained in a position where it keeps the threads tightened.

This object is accomplished by providing 45 means for releasing the take-up operating rod from its driving means when the fabric is being shifted from one figure to another thus causing the take-up means to remain in the position to which it has been raised to tighten the threads, said releasing 50 means being operated by the pitman rod through which the tensioning means is operated and at the time when the tensioning means has been released.

55 This and other objects of the invention will be more clearly understood from the

following detailed description and accompanying drawings, in which—

Figure 1 is a perspective view of a portion of the automatic mechanism with the embroidery machine attachment mounted 60 thereon;

Figure 2 is a perspective view of a portion of the automatic mechanism of the embroidery machine showing the mechanism operated upon the operation of the attachment for the embroidery machine; 65

Figure 3 is a top plan view of the embroidery machine attachment;

Figure 4 is a section on the line 4—4, 70 Figure 3;

Figure 5 is a top plan view showing how the pitman rod is engaged by the oscillating arm which operates it;

Figure 6 is a section along the line 6—6, 75 Figure 3;

Figure 7 is a side elevation of the take-up operating rod and the pitman rod for operating the tensioning means;

Figure 8 is a diagram showing how the thread is slackened when the take-up device is thrown forward; and 80

Figure 9 is a diagram showing how the thread is tightened and retained tight while the fabric is being moved from one figure to another by the operation of the embroidery 85 machine attachment.

In describing the embroidery machine attachment and its operation it will be necessary to set forth certain parts and movements of this well known embroidery machine which forms no part of this invention. 90

The drawings illustrate in heavy shaded lines my improved attachment to a well known type of embroidery machine in general use, the latter being illustrative and described with sufficient particularity to point out the construction and operation and advantages of my attachment. 95

It is to be understood that the operation of the embroidery machine is controlled by 100 a perforated paper or other strip (not shown), the strip functioning to control the embroidering operation in accordance with any given pattern.

Furthermore, the paper strip controls the 105 swinging movement of a horizontally movable lever 12 which is pivotally supported between its ends, as shown at 13, and has a bifurcated free end 18 for a purpose which will hereinafter appear. This lever 12 and 110

its adjacent co-operating parts are shown most clearly in Figures 1, 3, 4, 5, 6 and 7.

A represents a continuously rocking shaft which is caused to rock by means of an arm 11 which engages in a cam groove 57 in a cam 58. This shaft A is provided with a rocker arm 10' carrying a pin 10 at right angles thereto.

The pin 10 is adapted, when permitted, to engage in any of a series of notches 17 in the lower face of a foot 16, the latter elastically held in its lower normal position by means of a spring-pressed plunger 16' which engages the upper face of the foot and permits the foot to slide freely under the same. The foot is moved laterally into and out of operative engagement with the pin 10 by means of the lever 12 above referred to, as it will be noted that the bifurcated end 18 of this lever 12 straddles the foot. When the foot is moved by the lever 12 to a position out of engagement with the pin 10, its notched portions 17 rest upon fixed pins 17' and is held thereby against movement.

The foot 16 constitutes a fixed part of a pitman 15, the latter having a rack 19 thereon meshing with a pinion 20 on a shaft 21, so that the reciprocating movement of the pitman, due to the action of the rocker arm 10', will impart an intermittent oscillatory movement to the shaft 21. This shaft 21 carries a cam 22 which engages a finger 23 on a vertically movable rod 24, and a coil spring 22' exerts an upward pull on the rod 24. The rod 24 is connected at its lower end to a brake shoe 25 adapted to engage the tension roll 26 and is caused to move into holding engagement by the downward movement of the rod 24 and is released by an upward pull on the rod due to the spring 22'. 36 represents a shaft which is parallel to the tension roll 26 and carries a plurality of arms 28 which latter support a rod 28' over which the yarn or threads 27 are passed, and this rod 28' functions to take up slack in the threads or yarn, as will more fully herein-after appear. A crank arm 36' on the shaft 36 is connected by a link 35 with the crank arm 34 of a shaft 33 located above the shaft 36. Any suitable spring tensioning means may be provided to move the arms 28 to the position shown in Figure 9 as, for example, a flat spring 34' may be connected to a fixed part of the frame and exert downward pressure on the crank arm 34.

The shaft 33 is provided at one end with a crank arm 32 having a rod 31 pivotally connected thereto. This rod 31 I term a "take-up operating rod" which is formed at its other end with a notch 31' and a cam face 32' adjacent the notch. This notch 31' normally receives a pin 52' on a rocker arm 52, the latter fixed to a rocker shaft B. In the machine as heretofore made this rod 31 is permanently connected to the pin 52', and

by providing the construction of a notch to permit its removable connection with the pin 52' I am enabled to disconnect this rod so that the normal operation of the shaft 36 is stopped. It is with the provision of this notch 31' that my invention begins as all of the other elements (including the fixed pins 17') and structure referred to and described in the hereinabove descriptive portion of this specification have heretofore been and are now well known and widely employed in embroidery machines of the type shown. My reason for stopping this normal operation is that, when moving the cloth or material from one embroidering position to another, the threads are drawn and slackened so that, when the machine again operates, a sudden starting causes strain upon these threads which is apt to break them, and, by permitting this rod 31 to disconnect from the pin 52' and automatically bring about this disconnection, constitutes the real function of my attachment which will now be described in detail.

In the path of movement of the foot 16 I provide a lever 45 which is pivotally supported between its ends, as shown at 46, and at its other end is connected by a link 43 with the lower end of a lever 42, the latter pivotally supported between its ends as shown at 47. A forked arm 39 is pivotally connected to a fixed bracket 38 and preferably supported on an axle stub 49 in said bracket, and this forked arm 39 engages and is adapted to move the rod 31 above referred to. The connecting means between the arm 39 and the upper end of the lever 42 comprises a pair of rods 40 and 41 which are adjustably connected by a coupling member 51, and the end of the rod 40 is hook-shaped so as to engage about the arm 39 and move it in one direction. A coil spring 59' connects the rod 31 with the stub axle 49 so as to maintain the rod in the forked end of the arm 39.

My invention or attachment therefore consists of the lever 45, link 43, lever 42, rods 41, 40, arm 39, the spring 59', and the necessary supports for these parts. In addition, the improvement consists in providing the notch 31', in the rod 31 to permit the disconnection from the pin 52', and these parts are brought into operation when the end of the foot 16 engages a tongue or enlargement 48 on the free end of lever 45, as will now be explained.

In the ordinary operation of the machine, as controlled by the perforated sheet or strip above referred to, the shaft A is caused to rock through the medium of arm 11 and cam 58 so that the arm 10' and pin 10 are continuously rocked backwardly and forwardly. When the tension is to be applied on the tension roll, automatically the lever 12 is swung on its pivot to bring the foot

16 off of the fixed pins 17' and move the same laterally a distance sufficient to allow the pin 10 to engage in one of the notches 17 in the foot and impart a reciprocating 5 action to the foot. This reciprocating action will continue so long as the pin 10 is in one of the notches 17 and will, through the medium of the pitman 15, rack 19 and pinion 20, turn the shaft 21 to operate the 10 cam 22. This movement of the cam 22 exerts a downward pressure on the rod 24 to apply the brake shoe 25 to the tension roll 26. It is, of course, to be understood that the braking action is applied when the pit- 15 man 15 is moved in one direction and released when moved in the other direction, the coil spring 22' releasing the tension when permitted by the movement of cam 22. When the pattern of the embroidery is com- 20 pleted the perforations in the paper strip are such that they cause the lever 12 to oscillate intermittently and bring the foot 16 in position for engagement of the pin 10 with successive notches 17 so that a con- 25 tinuous longitudinal movement is imparted which causes the foot to engage the lever 42 and, through the medium of link 43, lever 42, rods 41, 40, and the arm 39, to force the rod 31 out of engagement with the pin 52' so that the shaft B can idly oscillate without moving the shaft 36 and its take-up 30 mechanism. When this occurs, the elastic means as, for example, the flat spring 34' engaging crank arm 34 as shown in Figure 35 2, will exert a sufficient pressure on the parts to move the shaft 36, arms 28, rod 28' to the position shown in Figure 9 and thereby take up the slack in the threads. When the machine again starts operation, the perfora- 40 tions in the controlling strip cause the lever 12 to move the foot 16 into and out of engagement with the pin 10 and so time these movements that the operation will cause the foot 16 to move in a direction directly op- 45 posite to that above described, the movement being a step by step movement until a normal position is reached, when only a reciprocating movement will be imparted to the foot to carry out the proper tensioning 50 of the tension roll in accordance with the pattern. When the foot is moving away from the lever 45 this, through the medium of the spring 59', will permit the rod 31 to move to a position to cause the pin 52' 55 to ride into the notch 31'. The extreme end of this rod 31 has a cam face 32' which guides the pin 52' into the notch or recess 31', and the spring 59' will hold the rod and the pin in operative engagement until forcibly disconnected by the operation of the arm 39, as above explained.

It will thus be noted that my improvement in the art consists in providing means which automatically operate to take up slack in the threads when moving the cloth from

one position for embroidering to another, and this is brought about by the disconnection of the rod 31 with the pin 52' through the medium of the parts above described controlled by the lever 45 which is engaged 70 by the foot 16.

Claims.

1. An embroidery machine attachment for use with embroidery machines provided with take-up means comprising means operated by the embroidery machine to release the take-up means in its thread tightening position from the embroidery machine when the fabric is being shifted. 75

2. In combination with an embroidery machine including a take-up and a take-up operating means, an embroidery machine attachment comprising means operated by the embroidery machine for releasing the take-up in its thread tightening position 80 from the take-up operating means stopping the operation of the take-up when the fabric is being shifted. 85

3. In combination with an embroidery machine including a thread take-up, a thread take-up operating rod, an embroidery machine attachment comprising means for releasing the thread take-up operating rod from said actuating means when the fabric is being shifted, and means operated 90 by the embroidery machine for disengaging said thread take-up operating rod releasing means from the thread take-up operating rod after the fabric has been shifted. 95

4. In combination with an embroidery machine including a thread take-up, a thread take-up operating rod for operating the thread take-up to move the latter to its thread tightening position, and means for actuating the thread take-up operating rod, an embroidery machine attachment comprising means for releasing the thread take-up operating rod from said actuating means to retain the take-up in its thread tightening position when the fabric is being shifted, and means operated by the embroidery machine for disengaging said thread take-up operating rod releasing means from the thread take-up operating rod after the fabric has been shifted. 100 105 110 115

5. In combination with an embroidery machine including a thread take-up, a thread take-up operating rod and means for actuating said thread take-up operating rod, an embroidery machine attachment comprising means for releasing the thread take-up operating rod from said actuating means to stop the operation of the take-up when the fabric is being shifted, said releasing means permitting the establishment 120 of connection between the thread take-up operating rod and said thread take-up operating rod actuating means after the fabric has been shifted. 125

6. In combination with an embroidery 130

machine including a thread take-up, a thread take-up operating rod for moving the thread take-up to its thread tightening position, and means for actuating the thread take-up operating rod, an embroidery machine attachment comprising means for releasing the thread take-up operating rod from the thread take-up operating rod actuating means when the thread take-up is in its thread tightening position to permit the movement of a fabric in the embroidery machine, said releasing means being disengaged from the thread take-up operating rod to permit the establishment of connection between the thread take-up operating rod and said thread take-up operating rod actuating means after the movement of the fabric.

7. In combination with an embroidery machine including take-up means, a take-up operating rod for operating the take-up means to move the latter to its thread tightening position before the work is shifted, means for actuating said take-up operating rod, tensioning means, and a pitman rod for operating said tensioning means, an embroidery machine attachment comprising means associated with said take-up operating rod for releasing the same from said

take-up operating rod actuating means before the fabric is shifted to retain the take-up means in its thread tightening position, lever means operated by said pitman rod when the tensioning means has been released, and means for conveying the motion of said lever means to the take-up operating rod releasing means to disengage the latter from the take-up operating rod.

8. In combination with an embroidery machine including a take-up, a take-up operating rod for operating the take-up to move the latter to its thread tightening position before the fabric is shifted, means for actuating said take-up operating rod, tensioning means, and a pitman rod for operating said tensioning means, an embroidery machine attachment comprising means associated with the take-up operating rod for releasing the latter from the take-up operating rod actuating means to retain the take-up in its thread tightening position while the fabric is being shifted, a lever operated by the pitman rod when the tensioning means has been released, and adjustable connecting means for utilizing the motion of the lever to disengage said releasing means from the take-up operating rod.

ANTONIO RAUSSE.
